Primary Examiner — Sheryl Lane*Assistant Examiner* — Aula Soroush(74) *Attorney, Agent, or Firm* — Muncy, Geissler, Olds & Lowe, PC(57) **CLAIM**

The ornamental design for a electronic inhaling device, as shown and described.

DESCRIPTION

FIG. 1 is a front elevational view of an electronic inhaling device showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, right perspective view thereof; and,

FIG. 8 is a rear, left perspective view thereof.

The broken lines in the drawings illustrate portions of the electronic inhaling device that form no part of the claimed design.
